UNITED STATES PATENT OFFICE

2,496,707

SPORTSMAN'S KNIFE

Robert P. Frye, Marlboro, Mass.

Application August 29, 1947, Serial No. 771,229

3 Claims. (Cl. 30—125)

1

The present invention relates to structural and functional improvements in a so-called sportsman's knife, that is, a hunting knife characterized by a special handle construction.

More specifically, novelty is predicated upon the provision on a huntsman's knife of a transparent hollow handle with a suitable closing cap for the outer end thereof, said handle providing a receptacle which lends itself adaptably for convenient storage of miscellaneous items such as matches, fishing hooks, string, first aid articles, etc.

Manifestly, I am sufficiently conversant with the prior state of the art to appreciate that the adoption and use of a recess in a handle and the closing of the recess with a cap or the like, whereby to provide storage space for articles, is not new. As a matter of fact the broad idea just touched upon is covered, for example in a patent granted to F. L. Putney 912,411 granted February 16, 1909.

My aim is to structurally and otherwise improve upon Putney and any other type handles in the same category through the use, choice, and selection of elements and parts not heretofore utilized in this specific line of endeavor.

In carrying out the principles of the invention I have evolved and produced a structural adaptation wherein the knife blade, which is more-or-less conventional in form, is attached to a head, said head being adapted to accommodate one end of a glass tube, there being an annular ring spaced from the head, and a connecting member between the ring and head, whereby to thus provide an adaptable mount for the cylindrical transparent tube or grip and closing cap means therefor.

Other objects and advantages will become more readily apparent from the following description and the accompanying illustrative drawing.

In the drawing:

Figure 1 is a view in side elevation with parts broken away and shown in section illustrating the improved handle construction and showing a simple screw plug constituting the closing cap;

Figure 2 is an enlarged fragmentary view showing the details of the principal parts which go to make up the completed handle construction;

Figure 3 is a perspective view of the adaptor means and blade carried thereby; and,

Figure 4 is a perspective view of the transparent cylinder forming the principal part of the hand grip.

Reference being had to Figure 3, which shows the skeleton construction, it will be seen that

5 this comprises a suitable blade 6 attached at its inner end to a disc-like head 7, said head having a reduced circular portion 8 defining a ledge 9 and a keeper to accommodate the end portion 10 of the glass, plastic or transparent cylinder 10. The afore-mentioned ring or annulus is denoted by the numeral 11 and this is provided internally with a keeper channel or groove 12. The annulus is connected eccentrically to the keeper 13 by way of a rectilinearly straight rod 13. The parts so far described form the afore-mentioned skeleton frame work 14 which includes, as a part, the blade 6.

Considering Figure 2 it will be seen that the 15 end portion of the glass cylinder fits over and surrounds the annulus 11 and is held in place by the marginal rim of flange 15 of the closing cap or plug 16. The latter includes a cylindrical plug portion 17 which telescopes into the annulus and which is provided at diametrically opposite points with pivotally mounted latches 18. The outer ends of the latches project through apertures provided therefor and are latched in the keeper groove 12. The cap and plug have 20 a central bore providing a passage 19 for a suitable finger operated plunger 20. The plunger is hollow and cylindrical and provided with a return spring 21 which is anchored in place on a suitable attaching pin 22 as shown in Figure 2. The plunger has diametrically opposite recesses 25 and the adjacent inner ends of the latches fit into the recesses. Hence, by pressing in the plunger against the tension of the spring means the latches are tripped and disengaged from the keeper groove 12. This makes it possible to 30 readily remove the cap. In placing the cap in position it is simply forced in and the latch is automatically snapped into place and holds the cap set.

35 If instead of using the latch equipped cap a simpler arrangement is preferred it is possible to provide the annulus 11a (see Figure 1) with internal screw threads to accommodate the screw plug 23 carried by the closing cap 24. It is obvious that by slipping the glass tube or cylinder over the ring 11, rod 13 and seating the inner end against the ledge 9 and placing the inner edge portion around the disc-like keeper 8, after the cap is fitted into the annulus, the glass 40 cylinder is thus held in assembled position. If desired, the glass cylinder may be fixed to the head 7 in any suitable manner whereby to obviate the necessity of holding same in place with the flange portion of the closing cap.

45 As previously stated the knife was primarily

designed for use by sportsmen and it features a hollow transparent handle with a quickly removable so-called butt cap. One's license may be placed in the handle and conveniently read through the transparent portion without the necessity of removal from the handle. The chamber provided by the handle may be utilized for containing and storing miscellaneous articles such as matches, pencils, keys, etc.

A careful consideration of the foregoing description in conjunction with the invention as illustrated in the drawing will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

Having described the invention, what is claimed as new is:

1. In a structure of the class described, a circular head having a reduced circular boss on one face, a blade attached to and projecting from the opposite face of said head, an annulus spaced from and in alignment with said head, a relatively narrow rectilinearly straight connecting rod eccentrically connected at opposite ends to said annulus and head, a hollow open-ended transparent cylinder forming a hand grip, said cylinder fitting over said annulus at one end, surrounding said rod and bearing at its opposite end against said head, and cap means removably fitted into said annulus and closing the adjacent end of said cylinder.

2. In a structure of the class described, a circular head, a blade attached to and projecting from said head, an annulus spaced from said head, a connecting rod between said annulus and

4
head, an open-ended transparent cylinder forming a hand grip, said cylinder fitting over said annulus, surrounding said rod and bearing at one end against said head, and cap means fitted into said annulus and closing the adjacent end of said cylinder, said annulus being provided interiorly with a keeper groove, said cap including a spring returned plunger and latches operatively connected thereto, said latches being projectible into said groove for purposes of removably fastening the cap in the annulus closing the annulus and adjacent end portion of said tube.

3. As a new article of manufacture, a one-piece skeleton unit for constructing a hollow handle equipped knife of the class described comprising a circular head having a reduced circular boss on one side defining a keeper and an annular ledge portion marginally surrounding said keeper, an annulus spaced from and parallel to said circular head, a linearly straight rod member eccentrically connected at one end to said boss and eccentrically connected at its opposite end to said annulus, and a blade mounted on the opposite side of said head.
